(57) **CLAIM**

The ornamental design for a cable block, as shown and described.

DESCRIPTION

FIG. 1 is a front elevational view of a cable block illustrating my new design;

FIG. 2 is a rear elevational view thereof;

FIG. 3 is a side elevational view taken from the left side of the cable block illustrated in FIG. 1;

FIG. 4 is a side elevational view taken from the right side of the cable block illustrated in FIG. 1;

FIG. 5 is a bottom plan view thereof;

FIG. 6 is a top plan view thereof;

FIG. 7 is a front elevational view of a second embodiment of a cable block illustrating my new design;

FIG. 8 is a rear elevational view of the embodiment illustrated in FIG. 7;

FIG. 9 is a side elevational view, taken from the right side of the cable block illustrated in FIG. 8;

FIG. 10 is an opposite side elevational view, taken from the left side of the cable block illustrated in FIG. 7;

FIG. 11 is a bottom plan view of the cable block illustrated in FIG. 8; and,

FIG. 12 is a top plan view of the cable block illustrated in FIG. 8.
